CIRCULAR KNITTING MACHINE

Robert Kirkland Mills, Sherwood, Nottingham,
England, assignor to Hosiery Developments
Limited, Nottingham, England

Application February 17, 1941, Serial No. 379,332
In Great Britain October 27, 1939

2 Claims. (CL 66—50)

This invention relates to improvements in circular knitting machines and the production of fabrics or hose or parts thereof and articles thereon. In particular the invention is concerned with circular knitting machines and the production of hose thereon of the type in which the hose is shaped or fashioned by the automatic introduction of needles from an inoperative to an operative position during the production of the hose.

It will therefore be appreciated that when commencing to knit the stocking blank there is a number of needles, coinciding with the back of the stocking, which are in an inoperative position, and such needles are selectively brought into operation to increase the effective width of the blank. After a blank has been completed and pressed off, knitting is automatically recommenced with the aforesaid needles in the inoperative position, and considerable difficulty has been experienced by virtue of the fact that when the previously formed blank was pressed off all of the latches of the needles were closed.

If now an inoperative needle is moved to the operative position immediately prior to its first knitting operation, there is a grave danger that the latch will not be opened, and in this event the needle will not take the thread and a press off may result, or in the alternative the requisite blank will not be produced. Various means for overcoming this trouble have been proposed, such as the use of a metal latch opener, or the use of a wire brush contacting with the needles at the station at which they are moved upwardly from an inoperative to an operative position.

The difficulty of correctly locating a metal latch opener so that it will contact with latches that are closed and ensure that they are opened by momentary engagement, and at the same time will not in any way injure the needles, will be appreciated by anyone skilled in the art. If in lieu of a latch opener of this type a wire brush, such as a circular wire brush, is utilised, one cannot be sure that a single upward movement of a needle relatively to the brush will ensure that the latch is opened. In point of fact, in practice it has frequently been found that the latch is not opened. Therefore with a view to overcoming this difficulty the present invention provides in a circular knitting machine of the type equipped with latch needles and arranged to produce a fashioned area of fabric by the automatic introduction of needles from an inoperative to an operative position as knitting proceeds.

5 a latch opener, and means for moving the inoperative needles relatively to it at each of a series of successive courses for the purpose of opening their latches. A further feature of the invention resides in the provision, in a circular knitting machine organised for production of a fashioned blank for a stocking or the like by rotational knitting from the toe-end upwards, the toe being added by knitting on another machine,
10 of means for pressing off all needles at the termination of a blank, other than a central group of needles, means for knitting roving courses and at least one slack running-on course on said central needles prior to the commencement of
15 the foot, and fashioning mechanism for progressively introducing, into activity at each side of said central group, the pressed-off needles in order to fashion the blank. A still further feature of the invention resides in the provision,
20 in a circular knitting machine organized for the production of a fashioned blank for stocking or the like by rotational knitting from the toe upwards, of means for pressing off, at the termination of a blank, all the needles other
25 than a central group of needles, means for operating said central needles to knit by rotation in the production of a foot portion of the blank, means for causing certain of said needles to take and knit a splicing thread in the production of
30 a spliced area at each edge of the blank, means for progressively varying the number of needles taking and knitting the splicing thread, and fashioning mechanism for progressively introducing,
35 into activity at each side of said central group, the pressed-off needles in order to fashion the blank. A further feature of the invention is concerned with means whereby the spliced stitches are slackened. A still further feature of the invention consists in the production of
40 one or more partial slack courses, that is to say one or more courses in which the splicing extends only part-way across a stocking blank, in order to facilitate the running-on of the fabric on to a heeling machine by which the heel tabs are subsequently knitted on the fashioned blank.
45 The foregoing and other features of the invention set out in the appended claims are embodied in the stocking blank, and/or in the machine, which will now be described as an example with reference to the accompanying drawings, in which
50

Figure 1 is a perspective view showing a stocking blank in the cylindrical form in which it is produced by the machine hereinafter described.

55 Figure 2 shows the blank laid out flat,

Figure 3 is an enlarged view of an area of fabric in said blank and is to some extent diagrammatic.

Figure 4 is a perspective view of the head of the knitting machine on which the blank is produced.

Figure 5 is a similar view looking from the opposite side.

Figure 6 is a perspective view of a detail.

Figures 7 and 7A together show an interior development of the cams of said knitting machine, and also show the needles and jacks.

Figure 8 shows a needle and its jack, and also illustrates the butts provided thereon at the various levels.

Figure 9 illustrates to some extent diagrammatically the operation of the pickers on the needle jacks for progressively narrowing spliced areas.

Figure 10 is a similar view but illustrating the progressive widening of the spliced areas.

Figure 11 is likewise a similar view illustrating the operation of the pickers in fashioning and mock fashioning.

Figure 12 is a plan, partly in section, showing the sinker cams and means for imparting an abnormal advance to certain sinkers.

Figure 13 is a sectional view on a somewhat larger scale further illustrating the last said means.

Figure 14 is a development illustrating the fact that certain sinkers are provided with long butts.

Figure 15 is an elevation of means provided for racking the pattern drum 53, hereinafter referred to.

Figure 16 is a further view of the latter.

Figure 17 is a plan looking on the top of the needle cylinder and showing the trapping and cutting mechanism for the ground thread G and locking thread L hereinafter referred to.

Figure 18 is a perspective view showing the manner in which said locking thread L is fed to and taken by the needles, while

Figure 19 is another perspective view showing the various feeders at the main feeding position.

The stocking blank shown in Figs. 1, 2 and 3 is made entirely by rotation, the number of needles that knit being varied to produce a shaped area of fabric the edges of which are connected by float threads. In Fig. 1 the fabric is shown at the right-hand side of the tube, while the float threads extend over the left-hand portion m of the tube circumference. The boundary of the knitted fabric at that portion of the tube which faces the observer in Fig. 1 is indicated by a chain dotted line. In Fig. 2 the development circumference of the needle cylinder is indicated by the dotted lines between which the dimension line marked C extends, and the boundaries of the fabric blank are indicated by full lines. The stocking blank is preferably produced according to my prior U. S. Patent No. 2,191,577, granted February 27, 1940, but it may be mentioned that the float threads may be cut out during the manufacture of the stocking instead of being cut out subsequently.

The stocking is knitted from the toe upwards and in Figs. 1 and 2 a blank with a French foot is illustrated, although it may be pointed out that an English foot may likewise be produced. At the commencement of knitting all needles other than the group of needles for knitting the instep and sole portion of the blank are pressed off, and a certain number of roving courses indicated at g are knitted. Next a slack running-on course

b is produced so as to permit the blank subsequently to be run-on to the needles of a footing machine by which the toe is knitted. Thereafter locked fabric according to my prior U. S. Patent No. 1,960,161 granted May 22, 1934, is knitted to form the foot and instep portion c but the marginal areas d of this portion are spliced as in a "slipper" foot. It will be noticed that each spliced area d is narrowed as knitting proceeds upwards from the toe, then continues at a constant width, and subsequently is again widened to a width somewhat less than the original width. In this second-mentioned widened area, indication lines marked f in Figs. 1 and 2 and shown on a large scale in Fig. 3 are produced. It is intended that the blank should be cut along these lines and the high heel portions a' herein-after mentioned shall be run-on to the needles of a heelng machine and heel tabs knitted on to said portions. In the production of these lines f matters are so arranged that the locking thread L is excluded from certain group of the needles at each edge of the blank for four courses so that unlocked fabric is produced. In the first 10 of these four courses, as shown in Fig. 3, slack stitches are produced on the said group of needles. In the second and third courses the splicing thread S is excluded from the said group of needles so as to give a clear indication of where 15 the blank is to be cut, and the extent of the cuts. The cuts at f are made in the unspliced portions of the second and third courses, as far as the commencement of splicing, and as a result they 20 terminate short of the inner margins of the spliced areas, as will readily be appreciated from 25 Figs. 1-3. Therefore the corners of the heels, being spliced, are strengthened. The fourth course is similar to the first course in that it is spliced but is slackened. Thereafter all the needles 30 so far in action produce locked fabric and the spliced areas are gradually narrowed to produce the high heel portions d' and at the appropriate time the splicing thread S is taken out. Knitting then proceeds until it is desired to widen 35 the fabric along the lines e to produce the widened portion g of the leg. This widening is effected by introducing additional needles into activity, and it is preferably accompanied by the production of mock-fashion marks. As shown 40 in Figs. 1 and 2 the lines of mock-fashion marks h may be parallel to the edges e of the blank so that in the finished stocking, when the edges of the blank are seamed together, said mock fashion lines are parallel to one another. Alternatively the lines of mock-fashion marks h may be 45 arranged to converge upwardly or downwardly in the finished stocking. The mock-fashion marks are preferably produced by tuck stitching, but they may be produced by any other known suitable means. After the leg has been widened to 50 a sufficient extent a further parallel portion of the blank is produced and then it is again widened as at i in the equivalent of what in a stocking produced on a Cotton's patent machine is known as the "thigh narrowings." This widening 55 at i may be accompanied by the production of mock-fashion marks j which in the finished stocking may be parallel or may converge upwardly or downwardly. By the widening at i the blank is brought to its maximum compass or width, so that that arc of the needle circle in which knitting does not take place is reduced to a minimum. Thereafter the fabric w for the 60 welt is knitted above the line marked k. This line k may be taken to indicate a narrow band of 65

reinforced fabric (knitted of a yarn R herein-after referred to) to hold the stitches when the welt is closed by sewing and/or it may be taken to represent a line of open-work such as is sometimes introduced immediately below the welt. The welt itself is knitted of a comparatively stout yarn which is marked W in Fig. 19, and it may or may not be made of locked fabric, as desired. At the line *l* a picot edge is formed, conveniently by causing spaced needles to hold their loops for a few courses. It is within the scope of the invention to knit that part *w* of the welt which lies below the picot edge *l* of the same or similar yarn (e. g. natural or art silk) as the leg or panel *g* and to introduce the stouter yarn W after the picot edge has been made.

The shaping of the blank is effected by introducing needles into knitting activity in the manner described in my said prior Patent No. 2,191,577, and it may here be pointed out that the parts herein indicated by the following references: 1, 2, 4-7, 9-22, 25-30, 32-36, 38-49 and 42 are identical with or are the equivalents of the parts having the same references in the said patent. Referring to Figs. 7 and 8, the needles are there shown at 1 and have knitting butts of contrasting lengths and two latches (for knitting the fabric of said prior Patent No. 1,960,161). There is a central group of needles indicated under the bracket MBN in Fig. 8 and having medium length butts. This central group is flanked by groups SBN having short butts. It is these three groups which knit the instep and foot portion of the blank. They are again flanked by groups LBN whereof the needles have long butts, and it is these needles LBN which are introduced into activity to widen the blank. In effect they are fashioning needles. Since in Fig. 8 the developed circumference of the needle cylinder is indicated by the dimensional arrow C it will be appreciated that between the adjacent ends of the groups LBN there is a portion of the needle circle which is not so far accounted for. This portion may be entirely void of needles. In other words there may be a gap in the circle of needles. This gap is indicated by the broken brackets G_b, and at each rotation of the needle cylinder (or of the cam box as the case may be) a floating thread (or two floating threads of locked fabric is being made) will be laid across it. Although this gap is a very narrow one when all the needles of groups LBN have been brought into activity, yet at the commencement of the stocking blank (when said groups LBN are inactive) the gap is quite wide and the floating threads *m* are long. In order to ensure that the first active needle at one side of the gap takes and knits the fed thread with accuracy, it is desirable to minimize the lengths of the floats. Therefore a few short butt needles indicated at G_n in Fig. 8 are introduced into this gap. These needles always knit, but they do not take any part in the formation of the stocking blank. They only produce narrow bands of fabric one of which is indicated at g_n in Fig. 1 within the gap so that the length of the floating threads *m* is always minimized, and cutting of the float threads is facilitated.

Beneath each needle and working in the same trick a jack 11 is located and under certain of these jacks 11 there are bits or subsidiary jacks 27. These jacks and bits have butts at various levels and of contrasting lengths as shown in Fig. 8. At the moment it is only necessary to refer to the jack butts 12 (Fig. 8) at one level. The jacks beneath the fashioning needles LBN are in-

dicated at F_j and have long butts. The jacks beneath the needles SBN have medium length butts. At each edge of the group of needles MBN there is a group of jacks having long butts. The 5 jacks of these groups and the jacks with the medium length butts are bracketed under the letters SJ, because they are the jacks which are used in splicing. Between the groups of jacks SJ and immediately at the centre of the needle group 10 MBN there is a group of jacks P having short butts.

At the right-hand edge of Fig. 7 two needles are shown. The lower one, on the extreme right, is in the inactive position in which its knitting butt will follow the inactive track 4; the butt of the raised needle pursues the active track 5. At the termination of one stocking blank all the needles will be pursuing this track 5 and it is first necessary to press off all the needles other than those that are required for the instep and foot of the next blank. This is effected by a 20 radially movable needle clearing cam 6 which is inserted to raise all the needles 1 to clear and by a cam 9 which is partially inserted so that 25 after the cleared needles have been lowered by cam 1 the long butt needles LBN are further taken down by cam 9 to the inactive track 4. At the same time that the needles pass down cam 9 the butts 12 of the jacks F_j pass down cam 21 30 to a lower inactive track 60. Therefore only the needles having butts SBN and MBN continue round to the main knitting cams KC. Cam 62 is also inserted to engage the butts LBN of the 35 fashioning needles running in track 4. The said needles are therefore raised so that their latches are brushed open by the latch-opening brush 63, said needles being subsequently lowered to the 40 inactive track 4 by cam 9. This occurs course after course until the fashioning hereinafter described commences. Thereby it is ensured that when the fashioning needles are introduced to knit their top latches are open.

The cam 6 is controlled by means of a bell-crank-lever 71 (Fig. 5) link 72, bell-crank-lever 45 73 and a thrust rod 74 from the main drum 123 of the machine. Cam 9 is controlled by a finger 75 on a vertical rod 76 which is itself rocked by a finger 77 engaged by a bell-crank-lever 78 operated by a push rod 79 from the main drum. The 50 latch-opening cam 62 (see Figs. 5, 6 and 7) is operated by a lever 80, link 81, bell-crank-lever 83, and push rod 84 from the main drum of the machine.

To return now to the knitting sequence, after 55 the foregoing movements of cams 6, 9 and 62, a few roving courses are knitted and the main stitch cam 2 is adjusted downwards by the usual thrust bar from the cam drum (not shown) to draw long loops for a toe running-on course. It 60 may here be mentioned that during the roving courses and slack course the locking cams LC (which manipulate the needles to take a locking thread L and therewith to lock the loops formed at the main feeding position) are retracted so that the needles produce unlocked loops. Likewise the sinker cams LCS associated with the locking cams LC are retracted. After the running-on course the locking cams LC and sinker cams LCS are pushed in. Their control is illustrated in Fig. 4 and that for the locking cams LC consists of levers 85, 85', links 86, 86', bell-crank-levers 87, 87', and thrust rods 88, 88' from the main drum of the machine. The control for the sinker cams LCS, comprises levers 124 and 125, arm 126 on vertical rock shaft 127, and a

lever 129 on the latter whereby it is rocked by a push rod 128 (having a suitable ramp) from the drum 123. It may also be mentioned at this stage, that when the locking cams are withdrawn the advance of the sinkers at the main knitting position is slightly increased so as to adjust the quality of the fabric. The mechanism for effecting this comprises a finger 88 on the vertical shaft 56 hereinafter mentioned as being included in the sinker controls, which finger is engaged and shaft 56 partially rotated when the locking cams are withdrawn.

Splicing now commences and to this end the splicing feeder SF is introduced. The bolt cam 13 (splicing cam) is moved in half way to lift the jacks SJ to cause the associated needles to take the splicing thread. It will not lift the jacks of groups FJ since they pursue the lower inactive track 60, and it will not lift the jacks of the central group P because they have short butts 12. The said cam 13 is controlled by link 90, bell-crank-lever 91, and push rod 92 (Fig. 5) from the main drum of the machine. Throughout the splicing the sinkers 43 associated with the splicing needles are given an abnormal inward advance so that the spliced loops are slackened and the slackening is substantially confined to the splicing. The means whereby this result is achieved is described later.

In order, however, to produce the gradual narrowing of the spliced sole areas *d* shown in Fig. 2 it is of course necessary gradually to reduce the number of jacks SJ that ascent the clearing cam 13, this reduction being effected from the inner ends of said groups SJ. Fig. 9 illustrates this operation. The jacks are picked down one by one by picking-levers 18, 18a provided on a pair of picker blocks 14, 14a. The block 14 is mounted on a ring 15 which encircles the needle cylinder and is capable of rotating thereon while the block 14a is carried on a similar ring 16. These two rings are urged in opposite directions, such that the picker blocks tend to approach one another, by springs 17, 17a which extend between suitable abutments on the rings and suitable abutments on the needle cylinder. The spring pressure tends to draw stops 64 and 64a together against a pin 65 on the needle cylinder. The pickers 18, 18a are operated by plungers 19, 19a respectively, themselves adapted to be displaced in a downward direction by cam 20. At the appropriate moment this cam 20 is moved inwards to a position wherein the plungers 19, 19a engage it. The controls of said cam are shown in Fig. 5 and comprise a lever 93 on a vertical rod shaft 94 which is rocked by a feeler 95 adapted to engage studs on a drum 58 hereinafter mentioned. The said cam may also be held out of operation position for prolonged periods by bluffing mechanism operated from the main drum of the machine and comprising lever 96, bell-crank-lever 97 and push rod 98. The sinker cam 48a hereinafter referred to is also inserted at the same time as the cam 20 in order to ensure that the spliced loops are slackened. When the plunger 19 is depressed by the cam 20 the picker 18 is likewise depressed and, engaging a projection 11b on the inner jack of the right-hand group SJ, lowers said jack until its butt 12 is brought to a position in which (as is shown at the right-hand side of Fig. 9) it will eventually meet cam 21 and be carried downward thereby. This brings the jack to the lower track 60 so that the needle associated therewith will not be elevated by cam 13 to take the splicing thread, but will knit the

ground thread only. This downward movement, completed by cam 21, brings a widened portion 11a of the jack located beneath the butt 12 into contact with the curved cam-like face of an abutment 22a on the picker block 14, and therefore causes said picker block to be displaced to the right in Fig. 9 against the action of spring 17 through one needle space. In effect then, the portion 11a serves as a locating stop for the picker. This takes place course after course, and in each course a similar operation likewise takes place on the jacks SJ of the left-hand group, but in this case the parts 11a of the successively lowered jacks engage the cam-like case of an abutment 22a on the picker block 14a and cause said picker block to be moved to the left in Fig. 9 against the action of spring 17a. This reduction in the number of splicing needles continues until the desired reduction in the width of the spliced areas is effected. Conveniently it continues until in each group SJ all the jacks having long butts and approximately half the jacks having medium butts have been lowered to the inactive track. When the desired reduction has been effected cam 20 is retracted to an inoperative position. Subsequently, when it is desired to widen the spliced areas adjacent to the heel line *f* the jacks are picked up again by the same pickers and this up picking operation is illustrated in Fig. 10. A cam 25 is inserted which raises the plungers 19, and 19a, and their respective pickers 18 and 18a to pick up the jacks until their butts 12 are brought into the range of cam 26 whereby said butts are brought to the operative track so that they eventually engage cam 13. Referring to the right-hand side of Fig. 10, it will be seen that the picker 18 is shown as elevating one of the jacks by engagement beneath the projection 11a thereon and this brings the butt 12 into position for engagement by cam 26. When said butt 12 is elevated by cam 26 the part 11a is removed from the cam-like abutment 22 so that the spring 17 pulls the picker to the left. Hence the said picker gradually approaches its original position. The left-hand picker operates in a similar manner. The cam 25 is controlled by arm 99 on a vertical rock shaft 100 (Fig. 4) carrying a feeler 101 co-operating with drum 58 and adapted to be bluffed from the main drum 123 of the machine by means of a curved push rod 102, bell-crank-lever 103 and other push rod mechanism.

Eventually the heel line *f* is reached and at the first course thereof it is necessary to exclude the locking thread L from certain needles and to cause said needles to produce long loops. To do so those of the lock cam LC that are shades in Fig. 7 are partially retracted to miss the butts of the needles of the two groups SBN. Therefore only the needles of the central group MBN continue to lock their stitches. Furthermore the sinkers 43 associated with the needles SBN which continue to produce unlocked but spliced stitches are given an additional forward projection by means hereinafter described so that the said spliced stitches are slackened. In the second and third courses the spliced thread is excluded from the needles SBN. For this purpose the splicing cam 13 is retracted half-way so that it misses the medium butt jacks of groups SJ, only the long butt jacks of groups SJ being elevated thereby to take the splicing thread. The fourth course is identical with the first course.

Thereafter the locking cams LC, and cam 26, are pushed in and the number of needles taking

the splicing thread is reduced to form the high heel parts *d*', this reduction being effected in the manner previously described with reference to Fig. 9. Finally the needle clearing cam 6 is completely retracted cam 13 is pushed right in, and the splicing feeder SF removed from feeding position, so that splicing ceases. It will be noted, however, that this insertion of cam 13 does not cause the needles LBN to take the splicing thread, because the butts of said needles pursue the track 4 and the butts 12 of their jacks FJ pursue track 60. Likewise cam 67 is pushed in to engage the long butts 37 on the lower jacks 27 that are associated with the splicing jacks SJ and to raise to track 61 all the splicing jacks 15 that have been picked down into track 60. As the jacks ride up cam 67 and cam 26 the parts 11a thereon are removed from the abutments 22, 22a on the picker blocks 14, 14a, and the latter are drawn together into the starting position by 20 springs 17, 11a. This cam 67 is operated by mechanism, shown in Fig. 5 as consisting of levers 113, 114, bell-crank-lever 115 and push rod 116, from the main drum of the machine. The introduction of cam 67 is also accompanied by the 25 introduction of cam 121, since these cams are connected by connections 114, 122. This cam 121 effects the withdrawal through the picker blocks 14, 14a of movable stops 130, 130a respectively associated therewith, which stops, when withdrawn, permit of the upward passage of the jack parts 11b, 11c, as will be appreciated from an 30 inspection of Fig. 10.

It is here convenient to refer in greater detail to the functions of cams 6 and 13. Throughout the foot up to the end of the splicing, cam 6 serves to raise the needles to clear in normal manner, while cam 13 raises selected needles to take the splicing thread. Subsequent to the termination of splicing, cam 6 cannot be employed 40 to clear the needles because certain needles will be required to tuck in the production of mock-fashion marks and a picot edge. Those needles that are not required to tuck therefore clear at cam 13, until after the picot edge has been produced, when cam 6 is inserted and cam 13 withdrawn.

To resume, after the spliced high heel parts have completed the knitting of locked fabric continues on needles SBN and MBN until it is desired to widen as at *e* by the introduction of the fashioning needles LBN gradually to reduce the gap GB. This introduction of the fashioning needles is effected by fashioning pickers, the operation of which is illustrated in Fig. 11. There 55 are two of these pickers and they respectively comprise picker blocks 29, 29a mounted on rings 30, 30a and biased away from one another by springs 32, 32a. The picker block 29 carries a plunger 33 working a picker 28, and the block 29a carries a plunger 33a working a picker 28a. These pickers operate underneath projections 27a on the lower jacks 27, and the plungers 33, 33a are displaced upwardly by a bolt cam 34 which is introduced at the appropriate time. This bolt cam 60 34 is controlled by means of a finger 104 associated with a feeler 105 for the drum 53, said finger and feeler being rotatable about rock shaft 106 and being arranged to be bluffed from the main drum of the machine by push rod 106 and bell-crank-lever 107 and a further push rod (not shown). The widening pickers start picking at the inner ends of the jack groups FJ and gradually move outwards and in Fig. 11 they are shown approximately half-way through the widening 70

operation. Their mode of operation is as follows: When for example the plunger 33 strikes cam 34 and is raised thereby the picker 28 strikes the projection 27a of that jack opposite which it is located and raises the jack 27 until the lower butt 35 with which it is provided is brought into the range of a cam 36. This cam continues the upward movement and brings the upper jack butt 12 from track 60 into track 61 and into the range of the elevating cam 26. Thereby a projection 27b on the lower jack 27 is raised until it engages the curved cam-like face of an abutment 37 on the picker block 29. The picker block is therefore forced to the left (Fig. 11) through one needle space against the action of spring 32 so that the picker 28 is brought into register with the next jack 27. The picker 28a operates in a similar manner except in that it moves to the right (Fig. 11) because considering the jack butts illustrated in Fig. 8 it operates at the right-hand end of the left-hand group of jacks FJ. When a jack is elevated by a picker 28a and cam 34 the part 27b is brought against the curved cam-like face of an abutment 37a on the block 29a and the said block is moved to the right against the action of spring 32a. Thus the two fashioning pickers continue to approach one another (Fig. 11) until they have picked nearly all the fashioning jacks, being then put out of operation by retraction of the cam 34. At the same time that the fashioning at *e* is effected the lines of mock-fashion marks *h* are also produced by pickers associated with the two blocks 29, 29a. It will be seen that in the upper part of each said block there is a mock-fashioning picker 38, 38a respectively operated by plungers 39, 39a from a bolt cam 40. This bolt cam 40 is controlled by a finger 108 on a vertical rock shaft 109 (Fig. 5) which is rocked by a feeler 110 cooperating with drum 53. Bluffing mechanism is also provided comprising a bell-crank-lever 111 and a push rod 112 operated from the main drum of the machine. As the plungers 39a, 39 are lowered in turn the pickers 38a, 38 are depressed to lower the associated jacks by engagement with the shoulders 11d thereon. This causes the jack butts 12 to be brought within range of the lowering face of the cam 13 so that the associated needles do not clear for one course, the jacks being subsequently raised by cam 26 whereby tuck stitches are produced, the frequency of the tuck stitches being determined by the frequency of the insertion of the cam 40, say every four courses. Since the mock fashioning pickers are supported on the same picker blocks as the fashioning pickers the mock fashioning marks are parallel with the edges of the block, the spacing being determined by the offset between each fashioning picker and its associated mock-fashioning picker. In Fig. 11 the mock-fashioning picker operates seven jacks inwards of the fashioning pickers although any other spacing may be adopted.

After the calf fashioning has been completed the fashioning cam 34 and the mock-fashioning cam 40 are taken out of operation for a predetermined period until they are again introduced for the thigh fashionings *i*, *j*, at which time the fashioning pickers complete the picking of the fashioning jacks FJ. Cams 62 and 9 are now withdrawn.

When the picot edge *l* is approached a further change of feeders is effected, a feeder PF (Fig. 19) being introduced for the predetermined number of courses. The picot edge is formed by means of butts 42 at the top of the

jacks, these butts being only provided on spaced jacks. A bolt cam 10 is introduced by finger 15 (being connected with cam 9 in such manner that cams 9 and 10 have converse movements) which cam 10 engages these butts 42 and lowers the jacks slightly so that they are taken down still further by the cam 13 which therefore causes the associated needles to tuck, the jacks being raised again in each revolution by cam 28.

At the termination of the welt all the needles LBN are pressed off by cams 6 and 9 as before mentioned. The fashioning needles are therefore lowered to track 4 and the butts 12 of their jacks FJ to track 60. At the same time, however, a cam 117 (Fig. 5) is inserted to retract the movable stops 131, 131a provided on the respective picker blocks 29, 29a, and it is the retraction of these stops that permits the parts 27a on the jacks to move downwards, as will be appreciated from a consideration of Fig. 11. The cam 117 is controlled by an arm on the aforesaid rock shaft 76 which controls cams 9 and 10.

The means whereby slack courses are produced are illustrated in Figs. 12-14. The sinkers 43 guided in the sinker ring 44 have butts which engage a cam track 45 in the sinker cap 46. Some sinkers have short butts 47a but the sinkers associated with those needles which are to produce the slack stitches at the heel lines *f* have long butts 47b. At that point in the needle circle whereat the sinkers are to be given a knocking-over advance there are two cams 48a and 48b. The former co-operates with the butts of all sinkers, while the latter co-operates only with the long sinker butts. The cam 48a is operated by lever 54, link 55, vertical shaft 56 and feeler 57 from cams 58a and 58b on the rings 15, 16 of the splicing pickers. Since the position of these rings at any time is the measure of the number of needles taking the splicing thread it will readily be seen that the cams 58a, 58b function to impart an excessive inward advance to those sinkers which are associated with the splicing needles. The other cam 48b is operated, to impart an extra advance to the sinkers associated with the needles that are to produce slack loops in the heel lines *f*, by means of a lever 49, vertical shaft 50 and feeler 51 from a pin or other projection 52 on a pin drum 53 which surrounds the base of the needle cylinder 66. The feeler 51 is capable of being bluffed, at the appropriate times, by linkage indicated generally at 70 and controlled by the drum of the machine. The feeler 51 is raised and lowered into and out of a position in which it is adapted to be displaced by cams 58a, 58b, by means of a lever 118 operated through push rod 120 from the main drum of the machine.

The various feeders which are located at the main feeding positions are shown in Figs. 4, 5 and 19. They are pivoted in a feeder bracket 137 on latch ring 144 and are operated by push rods 139-143, Fig. 5, controlled from the main drum of the machine. There is a push rod 139 for the main feeder MF, a push rod 140 for the splicing feeder SF, push rod 141 for the welt feeder WF, a push rod 142 for the picot feeder PF and a push rod 143 for a reinforcement yarn feeder RF. Alongside these push rods there is another push rod 138 which serves to control cutting mechanism mounted on a plate 150 which is supported in the interior of the needle circle by a bracket 151. Referring to

Figs. 5 and 17, on the plate 150 there is a spring clamping finger 148 for the ground thread C, and a trapper 146 and a cutter 147 therefor. There is also a spring clamping plate 148 and a cutter 149 for the locking thread L. The trapper 146 and cutter 147, and the cutter 149, are respectively operated by depending links 152, 153 from a lever 154 oscillated by said push rod 138.

10 The locking thread L is fed by means of a vertically slideable feeder plate 133 which is raised and lowered at the appropriate times by means of a lever 134 pivoted on a bracket 135 and engaging a stud 133 on said plate. This lever 134 is raised by push rod 136.

15 The pin drum or ring 53 which surrounds the base of the needle cylinder 66 above the driving gear 137 thereof is shown in Figs. 4, 15 and 16. Two sets of racking mechanism are required, because the size of the ring 53 necessitates a complete revolution thereof for fashioning and a complete revolution for splicing, and each revolution necessitates racking at different intervals. For the same reason two bluffing devices are provided. The ring 53 is provided with a ratchet wheel 155 which is engaged by two pawls 156, 157 which may conveniently be termed respectively the fashioning pawl and the splicing pawl since one is operative during fashioning and the other is operating during splicing. The fashioning pawl 156 is oscillated by means of a truck 160 engaging a cam 158 on the base of the cylinder. The bluffing mechanism for this splicing pawl consists of a hooked rod 162 which is connected to a lever 164 operated by the chain 166 of the machine and which serves to hold the truck 160 away from the cam 158. The splicing pawl 157 is likewise operated by a truck 161 engaging a cam 159 on the base of the cylinder and is bluffed by a hooked rod 163 connected to a lever 165 operated by the said chain 166.

20 It is to be understood that any known or convenient means may be provided for adjusting any or all of the needle and sinker cams referred to herein.

I claim:

1. In a circular knitting machine of the type equipped with latch needles and arranged to produce a fashioned area of fabric by the automatic introduction of needles from an inoperative to an operative position as rotary knitting proceeds: the combination of a feeding station for the active needles; a low inactive track for conducting the inactive needles during rotation past said station without knitting; an upper active track for conducting active needles to said station to knit thereat during rotation; a branch track leading upwards from the inactive to the active track for the introduction of inoperative needles into activity; a second branch track located between the first branch track and the said station, and leading downwards from the operative to the inoperative track for rendering the needles inoperative before they reach said station; a latch opener for engaging the latches of needles elevated through said first branch track; controllable cam means for elevating in each of a series of successive courses the inoperative needles through the first branch track to the latch opener; controllable cam means for lowering said needles in each of said courses through the second branch track before they reach the knitting station; and fashioning mechanism for operating on said inactive needles in other courses to

introduce them to the first branch track in fashioning by the gradual reduction in number of the inactive needles.

2. In a circular knitting machine of the type equipped with latch needles and arranged to produce a fashioned hose blank by the automatic introduction of needles from an inoperative to an operative position as rotary knitting proceeds, thereby to narrow a gap up the back of the leg of the hose blank: the combination of a central 10 group of instep needles having butts; a group of fashioning needles at each edge thereof, having longer butts; fashioning jacks below the fashioning needles; a group of splicing jacks below a certain number of instep needles at each edge 15 of the group of the latter; butts on said jacks, the butts on the splicing jacks being of two different lengths whereby each group of splicing jacks is sub-divided into an outer sub-group having relatively short butts, and an inner sub-group having relatively longer butts; a feeding station, including a ground thread feeder and a splicing thread feeder, for active needles; an upper active track for the butts of active needles to conduct said needles to the knitting station to knit in rotation; a low inactive track for the butts of inactive needles; an upper active track and a lower inactive track for the jack butts; a needle-ascent branch track for leading the needle butts up from the inactive to the active needle track; 20 a corresponding jack-ascent branch track for leading the butts of corresponding jacks up from the inactive to the active jack track; a needle-lowering branch track located between the aforesaid branch track and the feeding station, for leading needle butts down from the active to the inactive needle track before the needles reach 25 said station; a corresponding jack-lowering branch track for leading the jack butts down

from the active to the inactive jack track; a controllable clearing cam for elevating all needles in the active track, other than the instep needles, to clear; a controllable lowering cam for introducing the butts of said cleared needles into the needle-lowering branch track to press off; a controllable raising cam for diverting the butts of inactive fashioning needles in each of a series of successive courses of rotary knitting into the needle-ascent branch track to be subsequently lowered by said lowering cam; a latch opener for engaging the latches of said diverted needles; fashioning mechanism for operating on the fashioning jacks to raise their butts successively, in a series of fashioning courses, into the jack-ascent track, and for causing the jacks to elevate the butts of the fashioning needles into the needle-ascent track in the gradual introduction of said needles into activity; and means for producing spliced areas at the edges of the blank, including the heel, comprising a controllable splicing cam at the feeding station for operating on the butts of the splicing jacks to elevate said jacks and thereby the splicing needles, whereby the latter take the splicing thread and the ground thread, said splicing cam being movable between a position in which it engages the butts of all the splicing jacks and a position in which it engages only the butts of the inner sub-groups of splicing jacks and misses the butts of the outer sub-groups of splicing jacks, whereby the needles associated with said outer sub-groups do not take the splicing thread, and means for moving said splicing cam to the second mentioned position for at least one course in the production of demarcation lines at the heel extending inwards from the edges of the blank to points short of the inner boundaries of the spliced areas.

ROBERT KIRKLAND MILLS.
